F. P. KINTZELE.
SOFT COLLAR HOLDER.
APPLICATION FILED MAY 9, 1921.

1,385,176.

Patented July 19, 1921.

Inventor.
Felix P. Kintzele,
by Ripley Singeland,
His Attorney.

UNITED STATES PATENT OFFICE.

FELIX P. KINTZELE, OF ST. LOUIS, MISSOURI, ASSIGNOR TO KRISMAN-FREY JEWELRY MFG. CO., INC., OF ST. LOUIS, MISSOURI, A CORPORATION OF MISSOURI.

SOFT-COLLAR HOLDER.

1,385,176.

Specification of Letters Patent. Patented July 19, 1921.

Application filed May 9, 1921. Serial No. 433,096.

To all whom it may concern:

Be it known that I, FELIX P. KINTZELE, a citizen of the United States, residing at St. Louis, Missouri, have invented a new and useful Soft-Collar Holder, of which the following is a specification.

This invention relates to soft collar holders.

An object of the invention is to provide a soft collar holder, the length of which may be extended and contracted and which includes a spring normally tending to hold the parts in the positions of their shortest length.

Another object of the invention is to provide an improved soft collar holder for applying tension to the ends of the collar in a direction toward each other in a novel and effective manner.

There are other objects to be obtained by my present invention, all of which will be made apparent by the following description, reference being made to the drawing, in which—

Figure 1 is a front elevation of my improved collar holder.

Fig. 2 is a rear elevation.

Fig. 3 is a side elevation, and

Fig. 4 is a longitudinal sectional view.

As shown, my improved collar holder comprises two telescoping clasps. The part 1 telescopes within the other part, comprising the enlarged portion 2 and a portion 3 of smaller dimensions. Both of said parts are pressed to shape and are preferably arcuate in side elevation as shown. The part 1 telescopes within the enlarged portion 2 of the coöperating member and has its end bent to provide an abutment 4 for the inclosed expansion spring 5. The opposite end of the expansion spring 5 bears against the in-turned end 6 of the outer member. The sheet metal, of which the two members are formed, is pressed and shaped to provide hooks 7 on the ends of said members, respectively. The hooks 7 extend obliquely inwardly so that when applied to the outer part of a collar, they will make proper engagement.

The member 2—3 has ears 8 extending inwardly. A gripping or clasp member 9 has ears 10, embraced between the ears 8. A

pivot pin 11 supports the clasp member 9 in position, and a spring 12, wound around the pivot pin, actuates the clasp member 9 toward the outer portion of the member 2—3. The outer end of the clasp member 9 is bifurcated, receiving the hook or prong 7 between the arms 13 thereof.

A clasp member 14 is similarly constructed, having ears 15 embraced between ears 16 on the member 1, and pivoted on a pin 17. A spring 18 actuates the clasp or gripping member 14 to a position as shown. The outer end of the clasp member 14 is bifurcated, receiving the hook or prong 7 between the arms 19 thereof.

From the foregoing it will be seen that a constant tension will be exerted against the clasp members 9 and 14, to cause the collar holder to remain in proper connection with the collar. The spring 5 applies proper tension to the collar, and permits the length of the device to be extended or reduced to meet different requirements.

Movement of the part 1 within the co-operating part is limited by contact of the ears 16 with the end of the member 2—3.

I claim:

1. A soft collar holder, comprising two arcuate members, telescoping one within the other for a part of their length, an expansion spring within the two telescoping members limiting outward longitudinal movement thereof and actuating said members to telescope one within the other, a hook rigid with and extending inwardly from the concave side of each of said members near the outer ends thereof, and a pivoted clasp supported by each telescoping member and arranged to coöperate with the hook on said member for the purpose described.

2. A soft collar holder, comprising two arcuate members one of which is provided with an enlarged portion on its inner end and the other of which has its inner end telescoping within said enlarged portion, an expansion spring within the telescoping portions of said two members, means limiting extent of movement of one of said members within the other, a hook on the outer end of each of said members, and a clasp pivotally supported by each of said members to coöperate with said hooks respectively.

3. A soft collar holder, comprising a pair of telescoping members, a hook on the end of each of said members, and a bifurcated clasp supported by each of said members and embracing said hooks between the arms thereof respectively.

4. A soft collar holder, comprising a pair of telescoping members, a spring tending to telescope one of said members within the

other, an abutment limiting movement of one of said members within the other, a hook on the outer end of each of said members, a bifurcated clasp supported by each of said members and embracing said hooks between the arms thereof, and springs for actuating said clasps.

FELIX P. KINTZELE.
